CIGAR LIGHTER

Gustave F. Bahr, Fairfield, Conn., assignor to
 Automatic Devices Corporation, Bridgeport,
 Conn., a corporation of Connecticut

Application May 29, 1936, Serial No. 82,407

13 Claims. (Cl. 219—32)

This invention relates to cigar lighters, and more particularly, to devices of this character as used in automobiles and elsewhere.

Lighters for cigars, cigarettes and the like, of the kind just indicated, commonly comprise a holding device, in the form of a well and electrically served by connections to a source of current such that in the well there is a gap in an otherwise complete circuit, and an igniting unit 5 in the form of a plug adapted to be seated in and removed from the well for storage and use respectively, such unit having a heating element and carrying contacts so arranged that while the unit is in shallow or storage position in the well, 10 said circuit is open at said gap, but while the unit is in a deep or operative position in the well said gap is closed by way of a contact on the unit to place said heating element in the circuit for heating to incandescence and use.

20 In prior non-automatic lighters of this kind, the person operating the lighter, who is usually also the driver of the vehicle, must hold the igniting unit in its energizing position with one hand, while attending to steering of the vehicle with the other hand, and must periodically glance at and give his attention to the lighter to determine the state of readiness of same. This is a dangerous situation, and which might result in serious accidents.

30 It is an object of the present invention to obviate this disadvantage and danger, and this is accomplished by providing means whereby the igniting unit need not be held by the driver or operator in its energizing position, but instead is retained in this position by a detent mechanism 35 after being moved to that position by hand. Thus, the driver, except for the simple and quick operation of pressing in on the igniting unit, has both hands free to use in steering or otherwise controlling the vehicle, and may only glance at the lens of the lighter once or twice to determine when it is ready for use.

40 Or, the driver instead of glancing periodically at the lighter, may count, to a predetermined number, to determine when the igniting unit is ready for use.

45 Thus, according to the invention, there is provided a lighter not only with means for resisting the movement of the igniting unit from open-circuit position to closed, but also with detent means for holding the igniting unit in closed-circuit position, and this lighter greatly reduces the danger of accidents, when used in automobiles in place of prior lighters.

50 Also, in previously proposed lighters of this kind, but of the automatic type, thermostatically controlled means have been provided for automatically moving the unit within the socket to an inoperative position, that is, to break the energizing circuit for the heating element, when

said element reached a predetermined temperature hot enough to allow of the lighting of a cigar or cigarette therefrom after removing the unit from the socket.

According to the present invention, a double 5 detent lighter as above outlined is provided, wherein a thermostatically controlled means is employed, but wherein this means acts, when the heating element of the unit becomes heated to an incandescence sufficient for use, to break the energizing circuit for said element, without acting, directly or indirectly, to cause a relative movement between the socket and the unit.

10 As the invention is preferably carried out in its simplest form, the circuit breaking is followed by 15 an automatic remaking of the circuit if the unit is not withdrawn from the socket either completely or to shallow or storage position, before the heating element cools down too much. In other words, if after the unit is sent to deep or 20 operative position, it is inadvertently left there for a long period as when the driver's attention is required elsewhere for the moment, a heat-responsive means in the circuit of the heating element of the unit repeatedly acts to periodically 25 reenergize the heating element. If the driver, after moving the igniting unit to energizing position, should find when the igniting unit is ready for use, that his attention for the moment is required in connection with shifting gears, 30 steering or otherwise controlling the vehicle, he need not remove the lighter immediately but may wait until he is free to do so, and yet at such later time he will find the igniting unit in proper condition for use.

35 An arrangement of the kind above described permits a very simple and economical construction, and one which is at the same time practicable and desirable, as set forth.

40 Further, according to the invention, there is provided a special intermittently operated signal, visual or audible or both, arranged to operate when the heating element reaches suitable condition for use, and to continue such operation intermittently during the retention by 45 the element of that condition and until the unit is removed from deep or operative position in the socket.

45 Various other objects and advantages will be hereinafter referred to or become apparent.

50 In the drawing, which shows one form of the invention, that at present preferred:

55 Figure 1 is an axial sectional view, with the removable igniting unit, partially broken away and partially in section, shown in shallow or storage position in the socket.

Fig. 2 is a view similar to Figure 1, but showing said unit in deep or operative position in the socket and with the circuit for the heating element of the unit closed.

Fig. 3 is a view similar to Fig. 2, except that the unit is shown entirely in elevation and said circuit is shown open as it would be on the heating element of the unit reaching incandescence for use.

The cigar lighter of the present invention, in the exemplary embodiment thereof shown in the drawing, is of the so-called well type, for use in automobiles, and comprises a socket-carrying base member or carrier 10 for attachment to a panel 11 of an automobile, and a removable igniting unit 12 which is normally supported by the carrier, but which may be mechanically and electrically disconnected for manual transportation within the car and for handling by various occupants therein for the purpose of lighting cigars, cigarettes and the like.

The removable igniting unit 12, as the parts are shown, would ordinarily rest in the carrier 10 so as slightly to protrude therefrom as indicated in Figure 1, and the unit can be moved to the fully inserted position shown in Figs. 2 and 3, by a person desiring to place the unit in operative or energizing position for its heating element, thereby to condition the unit for removal from said base member and handling to light a cigar or cigarette.

The carrier 10 as shown comprises a sleeve 13 forming a deep socket 14, such sleeve having at its inner end an integral transverse wall 15. This sleeve is adapted to pass through a suitable aperture in the panel 11 of the instrument board, and is held in this position by a cap 16 screwed onto the outer end of the sleeve. One or more tongues 17 are lanced from the carrier, so that when the cap 16 is screwed up tight, the carrier 10 is clamped between such cap and the outwardly canted ends of said tongues, thus securely to mount the carrier on the panel 11. Any suitable form of holder may be substituted for that shown herein if desired.

The carrier 10 is preferably formed of sheet metal, and serves as a conductive element of the grounded portion of the circuit for the energizing current when the removable igniting unit is in deep or operative position in the socket 14.

The carrier 10 carries a current-conducting structure 19 suitably insulated from the carrier, said structure comprising the second contact to the heating element when the igniting unit is in deep operative position.

As here shown, said structure is a strip-like plate having each of its two arms bent as indicated at 19' to provide two substantially parallel contacts 19a.

The plate 19 is conveniently mounted at its central disk-portion on a metal stud 20. As shown, this stud has a shank the rear end of which is threaded, and carries at its front end an enlarged head 20a, beyond which is a reduced cylindrical extension headed-over at 20b so as suitably to anchor the plate in place.

The stud 20 is supported in a shouldered metal sleeve 21, but maintained out of contact therewith and with the carrier 10 by the insulation shown.

The stud is rigidly secured in the sleeve 21, by application of a primary nut 22 to the threaded end of the stud. A feed wire 23 is connected to the stud by a terminal clip 24, the latter being clamped in place by tightening up a secondary nut 25 on the threaded end of the stud.

Thus it will be seen that the carrier 10 is provided with contact members (the socket sleeve 13 and the plate 19) terminating at both sides

of the car circuit and insulated from each other.

The removable igniting unit 12 is shown as including a knob or handle 26 and a plunger section or body therebeyond adapted to fit slidably in the socket 14 for supporting the igniting unit therein. This knob is here an integral part of the body, which comprises a hollow tube of suitable insulating material; and at the inner end of such tube is secured a metal mount 27 for a heating element 28 and for a metal cup 10 29 within which said element is positioned.

This cup 29, and a pair of centrally apertured insulating disks 30, between which disks is seized an inner inwardly directed flange of the cup, are clamped on the mount 27 by means of a 15 stud 31 headed-over at one end as shown and carrying at its other end a slotted head 31a beyond an insulating collar 32. The collar 32 and an insulating washer combine with the disks 30 to insulate the metal cup 29 from the mount 20 27, except by way of the heating element 28 as will now be explained.

The heating element is, in the present case, in the form of a spirally wound resistance wire or band connected at its outer end to the periphery of the cup 29, and at its inner end set in the slot of head 31a of the stud 31.

According to the present invention, there are provided means for impositively holding the unit 12 in each of its two positions in the carrier 10, 30 the open-circuit storage position, and also the deep closed-circuit position. As shown, these means include in the present embodiment, oppositely extending tongues lanced from the cylindrical wall of the casing 13 as indicated at 33 35 and 34. The tongue 33 is normally resiliently biased to the position shown in Figure 1, and the tongue 34 is similarly inwardly urged.

For cooperating with the tongues 33 and 34, the metallic mount 27 is provided with a rear 40 peripheral outer edge of enlarged diameter, this edge of the mount presenting a generally rounded cross-section constituting an inclined shoulder 27a. Forwardly of the shoulder 27a is an oppositely inclined annular shoulder 12a on the exterior of the unit 12.

When the igniting unit is in the shallow or storage position shown in Figure 1, the tongue 33 is idle, but the shaped end of the tongue 34 coacts with the inclined shoulder 12a on the unit to 50 provide an impositive stop means for precluding accidental or casual movement of the unit either inwardly or outwardly of the socket 14.

Now, however, when the unit is manually moved to its deep or operative position, as shown in Fig. 55 2, the tongue 33 at its shaped end coacts with the inclined shoulder 27a on the mount 27 to retain the lighter in said position so that the hand can be removed from the knob. In this deep position the heating element will be energized in preparation for use.

Thus it will be seen that the lighter may be operated without requiring continual attention from the driver, and without requiring the use of his hand for an extending period, and therefore 65 the likelihood of accident resulting from attention given to the lighter by the driver when operating the vehicle has been materially reduced.

As indicated in the drawing, the rear wall or end of the mount 27 and the insulation disks 30 70 are matchingly apertured at a plurality of points around stud 31, so that, when the heating element 28 becomes incandescent, the glow of such incandescence will be visible at a translucent portion 26a of the knob of the unit, thus giving a visual 75

signal to the driver when the unit is ready for removal from the socket.

When the cigar lighter is out of use, the igniting unit is in its shallow or storage position as shown in Figure 1. However, when it is to be prepared for use, the unit is manually thrust to its deep or operative position as shown in Figs. 2 and 3, to cause the contact elements 19a to engage the metal cup 29 and make good electrical connection therewith. Thereupon, the energizing circuit for the heating element 28 is completed by way of the wire 23, the stud 28, the contacts 19a, the cup 29, said heating element 28, the stud 31, the mount 27, the tongue 33, and the sleeve 13 to ground. Upon the heating element 28 reaching incandescence, light therefrom will pass through the matched apertures in the washer 39, mount 27, and associated insulating washers, and through the bore of the igniting unit to the lens 26a, which will be illuminated so that the user may know that the igniting unit should be withdrawn before too great an elapse of time.

Although the device of the present invention, as thus far described, has utility and constitutes a distinct improvement over prior lighters, since it permits the driver of the vehicle to keep both hands on the steering wheel, driving conditions may at times so command the driver's attention that he will be unable to remove and use the heated igniting unit in proper time. In such event there is a possibility of the heating element becoming overwarm and eventually damaged. However, such an occurrence is of little consequence when compared with the major accident which might result to the automobile should the driver's attention be diverted by having to keep his hand continually on the lighter, as is the case with prior lighters of this type.

However, I have found it possible to control the temperature of the heating element so that it is confined within safe limits even though the driver be unable to remove the igniting unit when it has become initially hot for use, due to his attention being required in directing the vehicle.

In the embodiment of the invention shown herein in the means which I have provided for so controlling the temperature of the heating element is associated with the contact plate 19 so that said plate is operated, in response to a predetermined heating of the element, to move away from and out of engagement with the contact cup 39, so that the circuit through the element is broken. This means comprises a second plate substantially similar in size and shape to the plate 19 and secured thereto so that both plates act as a unitary bimetallic structure. When the element becomes heated, this structure deforms to the position shown in Fig. 3, and the energizing circuit is broken. All this time the parts remain as in Fig. 3, and unless the heating element becomes too cold to normally light a cigar or cigarette, the visual signal at the lens 26a will persist. As soon, however, as such glow tends to disappear or becomes faint, coinciding with a predetermined cooling of the heating element, the thermostatic structure just described, having correspondingly cooled, becomes restored to the position shown in Fig. 2. Thereupon, the circuit is again completed, and the heating element is again warmed to incandescence. Such alternately performed heatings and coolings of the element 28 continue, until the unit 12 is moved in the socket, either to remove the unit from the socket, or to move the unit to shallow or storage position.

Preferably, the bimetallic structure 19 is con-

structed to operate in such a manner that the temperature of the heating element will be maintained within a given useful range so that removal of the igniting unit at any time after the element has been initially heated will find said element in condition to light one or several cigarettes.

In order to provide means for giving a special signal that the unit is ready for removal from the socket, and particularly an attention-arresting one because an intermittently delivered one, the following means are provided.

A contact 35 is secured in place within the casing 13, as by a stud 35a, these parts being suitably insulated from the casing as shown. This contact 35 is positioned so that when the thermostat 19 is disposed as in Figures 1 and 2, the contact 35 is isolated from the circuit including the wire 23. When, however, the thermostat 19 is deformed as in Fig. 3, one of the contacts, 19a, engages the contact 35 in circuit with a suitable electrically actuatable signal device having its other terminal grounded on the shell 13, for operation each time the circuit last-mentioned is closed.

In the form shown, said circuit is supplied with current from wire 23, and by way of thermostat 19a, to contact 35, and through the signal device. Also, preferably, the signal device comprises a buzzer, the usual casing of which is conventionally illustrated at 36. The casing is grounded by its securing at 37 to the casing 13; current passes in the usual way to the ungrounded terminal of the buzzer from an insulated terminal 36a joined by a metal strip 38 to the contact 35 through the stud 35a mounting the latter. In the broader aspects of this invention, any other type of electrical signal may be substituted for the buzzer.

Once the unit 12 has been manually moved inwardly of the socket from the position of Figure 1 to that of Fig. 2, and has remained in the latter position long enough to heat the element 28 to incandescence, the signal in circuit with the contact 35 operates, that is, in the present case, the buzzer sounds; giving notice that the unit is ready for removal and use. If such signal is ignored, the heating element will cool, and with it the thermostat 19; the signal continuing until the thermostat moves away from the contact 35. The thermostat 19, on again making contact with the cup 29, again places the heating element 28 in circuit, and on said element again reaching incandescence, the signal will again be operated. Such signals will continue, intermittently, as long as the unit is left in the position of Fig. 2, due to the parts 19 and 35 becoming alternately arranged as shown in Fig. 2 and as shown in Fig. 3. An intermittent signal, and especially an audible one, which is at present preferred, is particularly attention-arresting, and, therefore, the most absent-minded user of the device, will, by the feature just described, always be given adequate warning in time to prevent other than a negligible unnecessary operation of the thermostat and other than a negligible unnecessary consumption of current.

It will be noted that the signal is given only after the circuit through the heating element has been broken, and the signal is discontinued before the circuit through the element is again reclosed. In other words, the signal is given during the interval when the heating element is in its most desirable condition, i. e., the condition of highest temperature for the particular thermostat employed. This is an important feature of the invention, since the user is most likely to remove

the igniting unit during this interval because the signal is then being given.

Variations and modifications may be made within the scope of this invention, and portions 5 of the improvements may be used without others.

I claim:

1. A lighter as defined in claim 10, wherein the holding means comprises a manually releasable detent holding the unit in deep or operative 10 position regardless of the temperature of the heating element.

2. A lighter as defined in claim 10, wherein the holding means comprises a manually releasable detent holding the unit in deep or operative 15 position regardless of the temperature of the heating element, said detent being impositive.

3. A lighter as defined in claim 10, wherein the holding means comprises a manually releasable detent holding the unit in deep or operative 20 position regardless of the temperature of the heating element, said detent being partially carried by the base structure and partially carried by the unit and being independent of said thermostatically controlled means.

4. In an electric cigar lighter, the combination of a holder; a heating element; an igniting unit carrying the heating element and insertable within and completely removable from said holder for use, said unit being manually movable in the holder to a shallow or storage position or to a deep or operative position; manually overcomable means for normally resisting the positioning of the igniting unit in operative position; means, separate from the last mentioned means, for holding the igniting unit in deep operative position; thermostatically controlled means carried by the holder for connecting the heating element to a source of current to cause heating of such element when the unit is in deep or operative 40 position and said heating element is below a predetermined temperature, said means including a thermostatic element deformable in response to heat from the heating element and when thus deformed directly breaking the connection of the heating element to said current source, whereby when the unit is left long enough in said deep or operative position, the heating element is alternately heated and allowed to cool a plurality of 45 times; an electrically operated audible signal; and means for operating such signal on the attainment by the element of said predetermined temperature.

5. In an electric cigar lighter, the combination of a holder; a heating element; an igniting unit carrying the heating element and insertable within and completely removable from said holder for use, said unit being manually movable in the holder to a shallow or storage position or to a deep or operative position; manually overcomable means for normally resisting the positioning of the igniting unit in operative position; means, separate from the last mentioned means, for holding the igniting unit in deep operative position; thermostatically controlled means carried by the holder for connecting the heating element to a source of current to cause heating of such element when the unit is in deep or operative position and said heating element is below a predetermined temperature, said means including a thermostatic element deformable in response to heat from the heating element and when thus deformed directly breaking the connection of the heating element to said current source, whereby when the unit is left long enough in said deep or operative position, the heating element is alternately heated and allowed to cool a plurality of 60 times; an electrically operated audible signal; and means for operating such signal on the attainment by the element of said predetermined temperature.

times; an electrically operated audible signal; and means for operating such signal on the attainment by the element of said predetermined temperature.

6. In an electric cigar lighter, the combination of a holder; a heating element; an igniting unit carrying the heating element and insertable within and completely removable from said holder for use, said unit being manually movable in the holder to a shallow or storage position or to a deep or operative position; manually overcomable means for normally resisting the positioning of the igniting unit in operative position; means, separate from the last mentioned means, for holding the igniting unit in deep operative position; thermostatically controlled means carried by the holder for connecting the heating element to a source of current to cause heating of such element when the unit is in deep or operative position and said heating element is below a predetermined temperature, said means including a thermostatic element deformable in response to heat from the heating element and when thus deformed directly breaking the connection of the heating element to said current source, whereby when the unit is left long enough in said deep or operative position, the heating element is alternately heated and allowed to cool a plurality of 15 times; an electrically operated audible signal; and means for operating such signal on the attainment by the element of said predetermined temperature.

7. In an electric cigar lighter, the combination of a holder; a heating element; an igniting unit carrying the heating element and insertable within and completely removable from said holder for use, said unit being manually movable in the holder to a shallow or storage position or to a deep or operative position; manually overcomable means for normally resisting the positioning of the igniting unit in operative position; means, separate from the last mentioned means, for holding the igniting unit in deep operative position; thermostatically controlled means carried by the holder for connecting the heating element to a source of current to cause heating of such element when the unit is in deep or operative 20 position and said heating element is below a predetermined temperature, said means including a thermostatic element deformable in response to heat from the heating element and when thus deformed directly breaking the connection of the heating element to said current source, whereby when the unit is left long enough in said deep or operative position, the heating element is alternately heated and allowed to cool a plurality of 25 times; an electrically operated audible signal; and means for operating such signal on the attainment by the element of said predetermined temperature.

8. In an electric cigar lighter, the combination of a holder; a heating element; an igniting unit carrying the heating element and insertable within and completely removable from said holder for use, said unit being manually movable in the holder to a shallow or storage position or to a deep or operative position; manually overcomable means for normally resisting the positioning of the igniting unit in operative position; means,

separate from the last mentioned means, for holding the igniting unit in deep operative position; thermostatically controlled means carried by the holder for connecting the heating element to a source of current to cause heating of such element when the unit is in deep or operative position and said heating element is below a predetermined temperature, said means including a thermostatic element deformable in response to heat from the heating element and when thus deformed directly breaking the connection of the heating element to said current source, whereby when the unit is left long enough in said deep or operative position, the heating element is alternately heated and allowed to cool a plurality of times; a second normally open circuit; a signal interposed in said circuit for operation when the latter is closed; and means for closing said circuit operating each time the heating element attains said predetermined temperature while the unit is in deep or operative position, said thermostatic element forming a part of the means last-mentioned.

9. In a cigar lighter, a holding device; an igniting unit supported by the holding device and completely removable therefrom for use, said unit being movable on a holding device from an open-circuit position to a closed-circuit position; a heating element carried by the igniting unit; 30 manually overcomable means for normally resisting the positioning of the igniting unit in closed-circuit position; separate means for holding the igniting unit in closed-circuit position until manually removed therefrom; means, separate from the heretofore mentioned means, for closing the circuit through the heating element to energize same when the igniting unit is in said closed-circuit position; heat-responsive means for intermittently opening and closing the circuit 35 through the heating element in response to the resultant heating and cooling of said element as controlled by the circuit; an electric signal; and means for operating the signal during the periods when the heating element is disconnected from its circuit as a result of heat from said element.

10. In an electric cigar lighter, the combination of a stationary base member; a socket in the base member; a removable igniting unit longitudinally slid able in the socket into a shallow inoperative position and a deep operative position; means 40 yieldingly holding said igniting unit in shallow inoperative position; a heating element on the inner end of the igniting unit and having a contact; and a contact on the socket adapted to electrically engage the contact on the heating element with solely a lateral pressure thereon so as to tend to hold the igniting unit in closed-circuit position, said contact on the socket being thermally responsive to the heating element so as 45 to expand laterally away from the contact on the heating element and interrupt the supply of current to the heating element when the heating element has been brought to a predetermined temperature.

11. In an electric cigar lighter, the combination of a stationary base member; a socket in the base member; a removable igniting unit longitudinally slid able in the socket into a shallow inoperative position and a deep operative position; means 50 yieldingly holding said igniting unit in shallow inoperative position; separate detent means for

holding the igniting unit in deep operative position a heating element on the inner end of the igniting unit and having a contact, said contact disposed on the igniting unit in a plane substantially normal to the path of movement of the latter in the socket; and a contact in the socket adapted to electrically engage the first-named contact and apply pressure on said first-named contact solely in the direction of the plane of the same so as to tend to hold the igniting unit in closed-circuit position, said contact in the socket being thermally responsive to the heating element so as to expand laterally away from the contact on the heating element and interrupt the supply of current to the heating element when the heating element has been brought to a predetermined temperature.

12. In an electric cigar lighter, the combination of a stationary base member; a socket in the base member; a removable igniting unit longitudinally slid able in the socket into a shallow inoperative position and a deep operative position; means yieldingly holding said igniting unit in shallow inoperative position; a heating element on the inner end of the igniting unit and having a contact, said contact disposed on the igniting unit in a plane substantially normal to the path of movement of the latter in the socket; a contact in the socket adapted to electrically engage the first-named contact and apply pressure on said contact in the direction of the plane of the same so as to tend to hold the igniting unit in closed-circuit position, said contact in the socket being thermally responsive to the heating element so as to expand laterally away from the contact on the heating element and interrupt the supply of current to the heating element when the heating element has been brought to a predetermined temperature; an electric signal; and means cooperable with said thermo-responsive contact 40 for operating the signal during the periods when the heating element is disconnected from its circuit as a result of heat from said element.

13. In an electric cigar lighter, the combination of a stationary base member; a socket in the base member; a removable igniting unit longitudinally slid able in the socket into a shallow inoperative position and a deep operative position; means yieldingly holding said igniting unit in shallow inoperative position; a heating element on the inner end of the igniting unit and having a contact, said contact disposed on the igniting unit in a plane substantially normal to the path of movement of the latter in the socket; a contact in the socket adapted to electrically engage the first-named contact and apply pressure on said contact in the direction of the plane of the same so as to tend to hold the igniting unit in the closed-circuit position, said contact in the socket being thermally responsive to the heating element so as to expand laterally away from the contact on the heating element and interrupt the supply of current to the heating element when the heating element has been brought to a predetermined temperature; an electric signal; and means cooperable with said thermo-responsive contact, including a second contact in said socket, for operating the signal during the periods when the heating element is disconnected from its circuit as a result of heat from its element.

GUSTAVE F. BAHR.
